(57) **CLAIM**

The ornamental design for a medicate container, as shown and described.

DESCRIPTION

FIG. 1 is a front perspective view of a medicate container in accordance with our new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The broken lines in the figures show unclaimed subject matter only and form no part of the claimed design.
